CLAIM

The ornamental design for a makeup tools bag, as shown and described.

DESCRIPTION

FIG. 1 is a side perspective view of the new design of an makeup tools bag according to an embodiment;

FIG. 2 is another side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof; and,

FIG. 9 is a side perspective view thereof, illustrating that the makeup tools bag is in an opened state.
The broken (dashed) lines show portions of the makeup tools bag that form no part of the claimed design.
